CLAIM

The ornamental design for a mechanical interpolation device, as shown and described.

DESCRIPTION

FIG. 1 is a front elevational view thereof.

FIG. 2 is a top elevational view thereof.

FIG. 3 is a rear elevational view thereof.

FIG. 4 is a left elevational view thereof.

FIG. 5 is a right elevational view thereof.

FIG. 6 is a bottom elevational view thereof; and,

FIG. 7 is a top left perspective view thereof.
